ELECTRIC VULCANIZING OUTFITS

Roland Dupont, Epernay, France

Application February 19, 1954, Serial No. 411,521

Claims priority, application France February 23, 1953

6 Claims. (Cl. 219—19)

The present invention relates to an electric vulcanising outfit of the quick-operated type for repairing rubber or fabric articles and comprising essentially a fixed supporting plate and a movable heating pad or box.

The scope of the present invention is to provide an apparatus of this type wherein the various steps of positioning the article to be repaired, and clamping, releasing and removing the heating system are effected very rapidly while ensuring the correct action thereof in the desired zone, so that the heat released will be concentrated exactly in the area to be vulcanised.

For permitting the quick operation of the heating system of the outfit, the heating pad is suspended for free oscillation at the front end of a rocking arm guided between a pair of vertical parallel supporting brackets of the apparatus and threaded on a pivoting rod above a coil spring urging the complete movable assembly upwards, in the axial direction of said rod, and a handwheel screwed on the upper end of this rod which makes it possible to clamp the arm downwards against the resilient pressure of said spring.

According to a complementary feature of the invention, a rocking stop may be positioned either beneath the rear end of the arm or away from this arm so that the latter can be swung rearwardly to raise the heating pad and free the repaired article or the plate on which another article to be repaired is subsequently placed.

A resilient substantially U-shaped frame structure may surround horizontally the plate on which the article to be repaired is placed, so as to hold the latter, and one arm of the resilient frame structure may act as a support for a pivoting guide member having a substantially semi-circular portion or like positioning element intended to engage the article to be repaired when the latter is placed upon the stationary plate for accurately centering thereon the article to be vulcanised, the centre of this semi-circular portion overlying that of the stationary, plate which in turn corresponds to the centre of the heating pad or box.

Within this heating pad or box the heat released by a resistance mounted therein is transferred to the lower face of the pad through a thin metal disc of reduced surface which is secured in the box in accurate relationship therewith so that its centre will register with that of the aforesaid semi-circular portion of the guide member when the latter is folded back onto the stationary plate carrying the article to be repaired.

The invention will be better understood if reference is made to the accompanying drawing forming part of this specification and showing diagrammatically by way of example one form of embodiment of the invention. In the drawing:

Figure 1 is a side-elevational and part-sectional view showing the outfit in its vulcanising condition;

Figure 2 is a corresponding vertical axial section showing the apparatus with its heating system raised from the work; and

Figure 3 is a part-sectional plan view from above of the supporting structure of the apparatus.

The electric vulcanising outfit according to the present invention and as shown in the drawing comprises essentially a bracket 1 formed integrally with a base plate 2 having holes conveniently spaced for securing the outfit to a bench or the like. The bracket 1 is also formed

2

integrally with a front arm 3 carrying a stationary plate 4 at its free end; this plate is adapted to receive a rubber disc 5 for supporting the article to be repaired.

The bracket 1 is also formed with an upward extension consisting of a pair of vertical parallel flanges 6, 7 having various horizontal holes formed therethrough. A transverse shaft 8 formed with a diametral threaded hole is journaled in bearings or adequate recesses formed in the flanges 6, 7. The threaded hole formed in shaft 8 is engaged by the correspondingly threaded end 9 of a rod 10 having its opposite end screw threaded as shown. The rod 10 is surrounded by a coil spring 11 and above this spring the rod has freely mounted thereon an arm 12 to be described presently; finally, the upper screw-threaded portion of rod 10 is engaged by an internally threaded nut or hub 14 rotatably rigid with a handwheel 13.

The arm 12 carries a pair of lateral reinforcements 15 acting as guide members to the arm to prevent it from oscillating about its axis while constantly causing the centre of the heating pad or box carried by the front end of the arm to register with the centre of the disc 5 supporting the article to be vulcanised.

For properly positioning the arm 12 the screws 16, held in the desired position through the flanges 6, 7 by the nuts 17, are tightened or released. These screws 16 are formed with flat inner ends frictionally engaged by the reinforcements 15, thereby providing an accurate alignment of the arm 12.

The front end of arm 12 is formed with a head 18 having a through bore 19 parallel to rod 10 and formed in turn with a chambered portion adapted to receive the upper end of a coil spring 20 the other end of which is received by a cavity 21 formed for this purpose in the upper portion of the heating box 22.

This heating box consists of a case having a lower face designed to be pressed against the article to be vulcanised which is carried by the resilient disc 5. A relatively thin metal disc 23 formed with a central hole is secured to the bottom face of box 22 and covered by a larger flanged disc 24 so that the peripheral flange of this disc 24 will bear against the bottom of the box whilst its centre engages the smaller disc 23, a rivet or screw 25 securing the pair of discs 23, 24 to the bottom wall of the case, as shown. The upper face of disc 24 carries an electrical heating resistance 26 of adequate value, which is insulated from the disc 24 and covered by an insulating pad 27. Convenient and known means are provided for feeding the resistance with heating current and automatically cutting the current supply when predetermined temperature conditions are attained in the outfit.

The heating box 22 is attached through a screw 28 to the arm 12 and extends through the bore 19 thereof so as to provide a fixation which is rigid when the device is inoperative and resilient when the device is operating; moreover, the arrangement is such that the heating box 22 may be inclined slightly if the article to be repaired is of unequal thickness. In fact, when the handwheel 13 is tightened the box 22 bearing on the article to be vulcanised compresses the spring 20 and the head of screw 28 is moved upwards, thereby freeing it from its fitting in the bore 19. Thus, the box 22 may be tilted somewhat since the shank of screw 28 is smaller than the bore 19 formed in the head 18. This shank is formed near its lower end with a collar 29 acting as a stop for the axial displacement of the screw and regulating automatically the initial compression of the coil spring 20. The lower end of screw 28 is formed with an extension engaging a hole formed in the insulating pad 27 of box 22, thereby providing a perfect centering while properly positioning this insulating pad 27.

A rocking stop 30 is pivotally mounted on a pair of

sockets 31 secured in the flanges 6, 7 through a pair of screws 32 which clamp a pair of washers 33 against the outer faces of the sockets 31. This stop 30 carries a pair of rear lugs 34 adapted to be positioned beneath the rear end of arm 12; it also carries a counterpoise 35 adapted for moving the stop 36 rearwardly so as to release the arm 12 and enable the latter to be swung from the position of Figure 1 to that of Figure 2.

The sockets 31 have their outer surfaces splined for engagement by correspondingly splined surfaces formed in the rear ends of the side arms of a resilient frame 36 rigidly secured by means of screws 32 tightened on the washers 33. The resilient frame 36 carries at its front end an insulating sheath 37, for example of rubber, to protect the operator's fingers from the heat released by the apparatus. This frame 36 also carries an inner guide member 38 pivotally mounted on one arm of the frame 36 and formed with an inner, substantially semi-circular portion 39. This guide member 38 is held in the proper longitudinal position by a pair of stop rings 40.

The operation of the apparatus described hereinabove is particularly easy and quick. With the arm 12 rocked upwards in the position shown in Figure 2 the article to be vulcanised is placed upon the supporting pad 5 while lifting slightly the frame 36 for inserting the article between this frame and the pad 5. Then the frame 36 will tend automatically to resume its initial position and will press the article to be vulcanised which will thus be properly held on the pad 5. Then the guide member 38 is lowered upon the article to be repaired for properly centering it. Then this article is slightly moved so that the puncture to be repaired be placed centrally of the semi-circular portion 39 of guide member 38. The still uncured patch (not shown), of same diameter as the semi-circular portion 39 of guide member 38, is placed upon the article to be repaired this guide member serving as a means for accurately centering the rubber parts. Finally, the guide member 38 is raised and swung back to its initial position (Figure 1).

By acting on the handwheel 13 and pulling it forward the complete clamping system will be rocked and the heating box 22 will overlie the article to be repaired, as shown in Figure 1. Then the rocking stop 30 is moved from the position of Figure 2 to that of Figure 1, so that the lugs 34 thereof will be positioned beneath the rear end of arm 12; however, it will be noted that the spring 11 urges the complete system upwards and that as a consequence a certain gap will always subsist between the lower face of the rear end of arm 12 and the upper face of the rocking stop 30.

By screwing in the handwheel 13 the arm 12 will be forced downwards. As the lower rear face of arm 12 engages the upper face of the rocking stop 30, this downward motion of this rear end is stopped. As the handwheel is further tightened, the head 18 of arm 12 continues its downward movement and the heating box carried thereby will be properly pressed on the article to be vulcanised.

Then the vulcanising step proper will take place very rapidly. Current is fed to the apparatus and the resistance 26, heat-insulated from the other components of the box, except through the small peripheral flange of disc 24 and the small disc 23, will be heated almost immediately. The heat will be transferred very quickly to the bottom wall of box 22 in the central portion contacting the disc 23. As a result, a very strong heat will be concentrated exactly at the centre of the box 22, and the heat will be reduced progressively toward the outer periphery of the box. Therefore, the patch will be quickly cured whilst the article to be repaired will not be unduly heated outside the central zone of vulcanising. Of course, the current supply will be cut when the proper degree of vulcanising is reached, through convenient and known means not within the scope of the present invention.

It will be readily understood that if the article to be repaired is thicker on one side than on the other side, the box 22 may be inclined in one or the other direction, as already explained hereinabove, due to the special coupling through the screw 28 which constitutes one of the features of this invention.

When the vulcanising is completed it will be sufficient to screw out the handwheel 13 one or two turns, tilt the rocking stop 30 to the rear and swing the complete heating and pressure system 12, 13, 22 in the same direction, that is, to the position indicated in Figure 2, for completely releasing the repaired article which can be removed immediately from the apparatus.

It will be readily understood that the example described hereinabove and described in the attached drawing is given merely by way of example and should not be construed as limiting the scope of the invention, as many constructional and dimensional modifications may be contemplated without departing from the invention.

20 I claim:

1. An electric vulcanizer for repairing articles of rubber or fabric, comprising a stationary support having a plate for receiving the articles to be repaired, a heating box for clamping these articles between it and said plate, a pair of substantially vertical parallel flanges carried by said support, a rod having a threaded upper end and adapted for pivoting between said flanges around an axis perpendicular to said flanges, a swinging arm having a central aperture for being freely and slidably mounted on said rod, a handwheel in threaded engagement on the upper end of said rod for clamping said arm downwards, means tending to raise said arm on said rod when said handwheel is loosened, means for suspending said heating box from the front end of said swinging arm and a rocking stop connected to said flanges for supporting in one position the rear end of said arm, when said handwheel is tightened.

2. An electric vulcanizer as claimed in claim 1, wherein said rocking stop consists of a pair of members each pivotally connected to one of said flanges, each of said members having a lug extending laterally of said flanges for engaging and supporting the rear end of said arm when said members are vertically positioned and said arm is in its clamping position and a counterpoise connecting said members and tending to pivot the same with said lugs out of their arm supporting position.

3. An electric vulcanizer as claimed in claim 1, wherein a pair of reinforcing members each extend along a side of said arm and a pair of screws are adjustably mounted through and extend laterally of said flanges each bearing against one of said reinforcing members for guiding the swinging motion of said arm.

4. An electric vulcanizer as claimed in claim 1, including a horizontal resilient frame surrounding said plate for holding the articles to be repaired onto said plate.

5. An electric vulcanizer as claimed in claim 1, including a horizontally positioned resilient frame surrounding said plate for holding the articles to be repaired onto said plate, a pivotally mounted guide member carried by said frame and adapted to be folded onto said plate upon the articles to be repaired whereby the latter can be centered in the area to be heated.

6. An electric vulcanizer as claimed in claim 1, including a pad to be heated by an electrical resistance element within said heating box and a thin metal disc centrally positioned between said heating pad and the bottom of said box.
